W. SANDS.

HAT HOLDER.

APPLICATION FILED DEC. 22, 1920. RENEWED DEC. 9, 1921.

1,419,945.

Patented June 20, 1922.

INVENTOR:

Walter Sande
BY HIS ATTORNEY
A.M. Carlsen

UNITED STATES PATENT OFFICE.

WALTER SANDS, OF MINNEAPOLIS, MINNESOTA.

HAT HOLDER.

1,419,945.

Specification of Letters Patent. Patented June 20, 1922.

Application filed December 22, 1920. Serial No. 432,592. Renewed December 9, 1921. Serial No. 521,248.

To all whom it may concern:

Be it known that I, WALTER SANDS, a citizen of the United States, residing at Minneapolis, in the county of Hennepin and State of Minnesota, have invented a new and useful Hat Holder, of which the following is a specification.

My invention relates to devices for holding hats when they are not in use. The objects are, first, to provide a hat holder that will not crush or mar the normal form or shape of the hat it holds; second to provide a hat holder which may readily be secured up under the ordinary top of an automobile with or without the use of tools, screws or nails, and may be readily secured to the back rest or under the seat of chairs and benches used in churches, theatres and public halls or to other structures.

In the accompanying drawing—

Fig. 1 is a transverse section of the top of an automobile, hack or other similar vehicle equipped with one of my improved hat holders. Fig. 2 is a top view of the device and a portion of the bow it is fastened to in Fig. 1, and a hat in dotted outline. Fig. 3 is a cross section on line 3—3 in Fig. 2. Fig. 4 is a cross section on line 4—4 in Fig. 2. Fig. 5 is an inverted view of Fig. 2. Fig. 6 is a left hand end view of Fig. 5. Fig. 7 is a modification of Fig. 5. Fig. 8 is a portion of Fig. 7 further modified. Fig. 9 is a still further modification of certain parts of the device.

Referring to the drawing by reference numerals, 10 designates the usual canvas top or other flexible top stretched over bows 11 of the roof or top of an automobile, hack or bus. In such vehicles space is often so limited that in warm weather, when it is desirable to remove the hats from the head, there is no convenient place to put them except up under the top of the vehicle; my device is therefore especially designed 45 to go in said place and to be fastened to the bow 11, preferably without screw, nails or bolts, so it may be readily detached, moved and attached wherever there is best room for it.

With said end in view the device consists of a metal plate 12 having its ends hook shaped at 13 (see Fig. 3). This plate is inserted between the coverings 10 and the bow 11 upon which it rests, and in its 55 hooks it supports the longer bars 14 forming a part of a wire yoke 14, 15, whose

short bars 15 are held firmly up under the bow by the resilient long bars 14. One end bar of the yoke may be plain, as 15, while the other end bar, 15*, is a continuation of 60 one of the bars 14 and is cold-shut at 16 about the end of the other bar 14 as at 16* and thereafter forms a hook or guard 17, (see Fig. 6). This guard 17 serves to engage and hold or aid in the support of the 65 projecting finger 18 of an approximately circular yoke or hat support 19, which is offset downwardly at 21 and 22 and is formed with two arms 20, the ends of which may be secured to the yoke or frame 14—15 in various manners, and are spring held upward against the bow 11 or other support in different manners.

Thus in Figs. 2, 4 and 5 a sheet metal yoke 23 is closed about the bars 14 of the 75 frame yoke and the ends of the arms 20 are held tightly in said sheet or band metal yoke; and each arm 20 is made extra resilient by having a spiral-shaped portion 20*.

In Fig. 7 the arms 20 have no springs but 80 their ends are bent angularly into apertures 24 of the yoke 23 to which they are thus pivotally connected because they are constantly subject to upward pressure by arms 25 of two springs 26, which may be formed 85 at opposite ends of a wire having at its middle a loop 27, secured by rivets or like means 28 to the sheet metal yoke 23.

In Fig. 8 the structure is the same as in Fig. 7 except the arms 20 extend beyond 90 the yoke 23 and are formed with eyes 29 pivotally embracing the short bar 15 of the frame yoke.

In Fig. 9, 11* designates any object or structure to which the device may be secured by screws 30 through yoke or plate 23, the frame 14—15 being dispensed with. In this view is also shown that the type of springs 26* and loop 27* may be formed directly at the ends of arms 20, and also 100 that the arms 20 may carry two rings 19* by which to hold two hats in one device if so desired.

In the use of the device after it is secured in place as already explained, the yoke 19 is 105 taken hold of and swung sufficiently away from the frame 14—15 or the stationary object 11 or 11* to admit the hat to slip into the yoke or ring 19, like the hat 31 in Fig. 1, whereupon the yoke is allowed to rise 110 and hold the hat with its brim supported on and held by the ring 19 against the

- object supporting the device. It will be noted that the edges 31* of the brim and the crown of the hat contact with nothing and can thus not be deformed by the device.
- 5 If the hat is very heavy and the automobile moves fast over a rough road it will be well to let the projecting finger 18 be engaged in the hook 17 by springing the yoke laterally, the yoke 19 being limber enough 10 to admit lateral movement for said engagement and disengagement.

In Fig. 7 is shown that the yoke 19 may have an overlapped joint 32, making it automatically adjustable by simply spreading 15 it when a hat is of extra large size. For ordinary and small hats the normal size of the yoke is supposed to be all right.

What I claim is:—

1. A hat holding device comprising a 20 frame securable to a fixed object, a hat supporting device mounted on the frame and comprising a spring pressed swing-

able yoke attached at one end to the frame and adapted to embrace loosely the crown or body of the hat and press the brim of 25 the hat gently against the object holding the frame, said swingable yoke being adjustable as to its width by having its swingable end formed with a sliding joint.

2. The combination with a bow or similar frame strip of a canvas-covered vehicle top, of a plate adapted to be inserted between the bow and the canvas, said plate having hook-shaped ends projecting beyond the opposite edges of the bow, a resilient 35 yoke having longitudinal bars adapted to be sprung into said hooks and thereby hold the ends of the yoke firmly against the strip, and a hat supporting device secured to said yoke.

In testimony whereof I affix my signature.

WALTER SANDS.
